(57) **CLAIM**

The ornamental design for a set of hitch handle and wheel supports for a portable blind, as shown and described.

DESCRIPTION

FIG. 1 is a perspective view of set of hitch handle and wheel supports for a portable blind in a deployed configuration, showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a perspective view thereof, in a stowed configuration.

FIG. 9 is a perspective view of a wheel assembly thereof, in a deployed configuration, shown separately for ease of illustration.

FIG. 10 is a front elevation view of the wheel assembly of FIG. 9.

FIG. 11 is a rear elevation view of the wheel assembly of FIG. 9.

FIG. 12 is a right side elevation view of the wheel assembly of FIG. 9.

FIG. 13 is a left side elevation view of the wheel assembly of FIG. 9.

FIG. 14 is a top plan view of the wheel assembly of FIG. 9.

FIG. 15 is a bottom plan view of the wheel assembly of FIG. 9.

FIG. 16 is a perspective view of the wheel assembly of FIG. 9, in a stowed configuration.

FIG. 17 is a front elevation view of the wheel assembly of FIG. 16.

FIG. 18 is a rear elevation view of the wheel assembly of FIG. 16.

FIG. 19 is a right side elevation view of the wheel assembly of FIG. 16.

FIG. 20 is a left side elevation view of the wheel assembly of FIG. 16.

FIG. 21 is a top plan view of the wheel assembly of FIG. 16.

FIG. 22 is a bottom plan view of the wheel assembly of FIG. 16.

FIG. 23 is a perspective view of a handle assembly thereof, in a deployed configuration, shown separately for ease of illustration.

FIG. 24 is a rear elevation view of the handle assembly of FIG. 23.

FIG. 25 is a front elevation view of the handle assembly of FIG. 23.

FIG. 26 is a left side elevation view of the handle assembly of FIG. 23.

FIG. 27 is a right side elevation view of the handle assembly of FIG. 23.

(Continued)

FIG. 28 is a top plan view of the handle assembly of FIG. 23.

FIG. 29 is a bottom plan view of the handle assembly of FIG. 23.

FIG. 30 is a perspective view of the handle assembly of FIG. 23, in a stowed configuration.

FIG. 31 is a rear elevation view of the handle assembly of FIG. 30.

FIG. 32 is a front elevation view of the handle assembly of FIG. 30.

FIG. 33 is a left side elevation view of the handle assembly of FIG. 30.

FIG. 34 is a right side elevation view of the handle assembly of FIG. 30.

FIG. 35 is a top plan view of the handle assembly of FIG. 30; and,

FIG. 36 is a bottom plan view of the handle assembly of FIG. 30.

The broken lines illustrate portions of the set of hitch handle and wheel supports for a portable blind and form no part of the claimed design.
